UNITED STATES PATENT OFFICE.

HENRY W. LARSSON, OF SPRINGFIELD, MASSACHUSETTS, ASSIGNOR TO LARSSON WHIP COMPANY, OF SPRINGFIELD, MASSACHUSETTS, A CORPORATION OF MASSACHUSETTS.

MACHINE FOR LONGITUDINALLY DIVIDING STRIPS OF RATAN.

SPECIFICATION forming part of Letters Patent No. 694,869, dated March 4, 1902.

Application filed June 26, 1901. Serial No. 66,153. (No model.)

To all whom it may concern:

Be it known that I, HENRY W. LARSSON, a citizen of the United States of America, and a resident of Springfield, in the county of Hampden and State of Massachusetts, have invented 5 certain new and useful Improvements in Machines for Longitudinally Dividing Strips of Ratan, of which the following is a full, clear, and exact description.

This invention relates to machines for splitting or longitudinally dividing strips of ratan, wood, &c., and has for one of its objects the provision of a machine whereby a strip which is subsequently triangular or in the 15 form of a segment in cross-section may be slit 20 or divided longitudinally and in such a manner that the pair of component parts of the strip after it has been slit, which are complementary to each other, will be tapered 25 endwise and of such a peculiar cross-sectional form as to require in the further operations thereon to bring them to the form of long slender conic segments or whip-sections a much less proportionate trimming or removal 30 of surplus stock at the small frail end portion than at the more bulky and stable butt-end portion.

My invention has, furthermore, for its object the provision of means whereby the effective working zone of the cutter or other slitting-tool may be varied relatively to the longitudinal axis of the strip and also whereby the extent of working movement or effective working zone may be more or less, as desired, for a given line of work.

My invention has, furthermore, for its object the provision of a guide or similar device whereby the strip after it leaves the feeding device may be properly guided during its longitudinal travel, so as to bring the strip into engagement with the knife in proper position laterally of the strip, and also the combination with said guide of means for seating and retaining the strip in the guide.

My invention has, furthermore, for its object the provision of a device whereby the strip after it has passed through the feeding means or is released therefrom may be ejected and fed past the slitting-knife preparatory

to the feed of another strip into engagement 50 with the knife.

A further object of my invention may be found in the provision, in combination with other parts of the mechanism, of a member which I preferably term a "separating" member 55 and which serves for the purpose of separating the component parts of the strip after the latter has been slit and to keep said component parts away from the sides of the knife or cutter, the life of which will therefore be considerably enhanced.

Further objects of my invention reside in the particular construction and organization of the several parts of my machine, as will be hereinafter described, and pointed out in the 65 claims.

It will be here stated that the present improved machine has been devised with especial reference to the production from slabs or strips of ratan, each of which is in the form 70 of the segment of a cylinder, being of sector shape cross-sectionally at all points in its length, of two complementary divisions of the original segmental piece, each of which is tapered from end to end and comprises in all 75 points in its length cross-sectional bulk or area exceeding the cross-sectional area at corresponding points of a conic segment, with, however, a greater excess or surplus relatively to any given cross-section of the conic segment 80 at the larger or butt half or end portion than at the forward half or tip portion, all so that in the final trimming, whereby the strip of the true form of the conic segment or of a form suitable for a component of a whip-stock is produced, there will be required the removal of but a comparatively small amount of the stock at the tip end, which could not withstand without breakage a very considerable trimming, the removal of the greater surplus being done 90 at the butt-end, where the strip has sufficient stability to withstand such proportionately greater removal of stock, and for the production of a machine capable of slitting or dividing the segmental strips into the two parts 95 having shapes such as referred to, the advantages of which have been stated, the invention consists in the combinations and rela-

tive or coöperative arrangements of devices or mechanisms, and in the constructions and combinations of parts, all substantially as hereinafter set forth, and covered in the 5 claims.

In order to explain the operation of my improved machine in a clear and concise manner, I have illustrated in the accompanying drawings a mechanism which is adapted for 10 slitting a strip of ratan, such strip forming a sector-like portion of an originally cylindrical body and being of substantially similar cross-section throughout its length.

In connection with the feeding means 15 whereby a strip is propelled and forced into engagement with a suitable cutter or slitting knife I deem it essential to provide a device whereby the strip itself may be maintained in its position without any deviation during 20 its longitudinal travel, so that the knife or cutter may perform its work evenly and accurately, the knife being preferably disposed so that the cutting edge thereof will be in parallelism with the cut which the knife 25 is supposed to make near the middle portion longitudinally of the strip.

While from the foregoing it will be understood that the position of the strip is in the present instance practically predetermined 30 and unalterable, means are provided whereby the knife or cutter is gradually caused to traverse across the path of the longitudinally-moving strip, so that said cutter may separate the strip into the two component parts, the 35 slitted sections of which will be of a length corresponding to the ratio of longitudinal movement relatively to the crosswise movement of the knife.

In some cases it may be advantageous or 40 desirable to vary the effective working zone of the knife relative to the longitudinal movement of the strip, so that said knife may be caused to engage the strip and slit the same nearer the central body portion of the strip 45 than at other times, or, vice versa, so that practically my improved machine is adapted for producing whip-stock-forming strips having the tapered portions thereof different, both in degree and in disposition, relatively to the 50 whole length of the strip.

In the accompanying drawings, Figure 1 represents a top view of my improved machine. Fig. 2 is a side view thereof. Fig. 3 is an end view looking from the left of Fig. 2 55 and on an enlarged scale. Figs. 4 and 5 illustrate a top view and vertical section, respectively, of a part of the feeding mechanism, the guide, and also the cutter or knife. Fig. 6 is a perspective view of the slide whereby 60 the cutter, mounted in a holder thereon, is carried and caused to traverse the path of the longitudinally-moving strip. Fig. 7 is a perspective view of the knife-holder detached from the slide. Fig. 8 is a diagram illustrating in end view the strip which is to be operated upon by my improved machine and also showing in what manner such strip is ob-

tained from the originally cylindrical body of ratan. Fig. 9 is a top view of a strip and illustrates the diagonal line of cut made by the 70 knife. Fig. 10 shows a series of diagrams illustrating sections of the strip taken at regular intervals in the length thereof and illustrating the formation of the two complementary parts thereof; and Fig. 11 shows a side view 75 of one of such complementary parts, the same being exaggerated greatly from the appearance of the strip as produced usually in practice in that while the cross-sectional size is increased the length of the strip is but a fraction 80 of that usually made, such exaggeration being, however, to the end of practicability of illustration and for the purpose of the better disclosing the salient feature or form of the strip, the production of which constitutes 85 a controlling motive in the peculiar organization of the present machine.

In the accompanying drawings, in which similar characters denote similar parts, *a* represents the frame or table of the machine, supporting in journals *b* a horizontally-disposed shaft *c*, one end of which carries a belt-pulley *d*, to which power may be imparted from any ordinary source. Near its other end the shaft *c* carries a gear *e* in engagement with 95 an intermediate gear *f*, journaled on an adjustably-mounted stud *g*, which is supported in a slot at the rear of the frame, said gear *f* being in engagement with a gear *h*, secured to the arbor of one of a series of feed-rollers 100 *i*, all of which are caused to coöperate—as, for instance, by pinions *j* and intermediates *k*. Coöoperating with the rollers *i* are a set of friction-rollers *l*, whereby the strip to be operated upon is forced into contact with 105 the feed-rollers *i*, said friction-rollers *l* being more clearly illustrated in Figs. 3 to 5, inclusive, in which they are illustrated as being loosely mounted upon bars *m*, which are pivoted near their rear ends, as at *n*, in a suitable framework *o*. The bars *m* are forced downward in the present instance by angle-levers *p*, which are fulcrumed in the frame 110 *o* and are provided with antifriction-rollers *q* in engagement with said bars, while springs 115 *r* are employed for engaging the other arms of the angle-levers *p*, and thus bring the antifriction-rollers *l* into contact with the strip, which will thereby be forced into engagement with the feed-rollers *i* above referred to. 120

Adjusting-screws, such as *s*, may be employed for forming a stop for the downward movement of the bars *m*, so as to prevent the rollers *l* and *i* from coming into direct contact with each other after a strip has passed 125 them.

The shaft *c* is herein shown as having a worm *t* in engagement with a suitable worm-gear *u*, secured to a vertically-disposed shaft *v*, which may be journaled in the table *a*, said 130 worm-gear *u* carrying on its upper surface a roller *w*, adapted for engaging a lever *x*, which is fulcrumed at *y* on the table and the free end of which is connected—as, for in-

stance, by a link ϵ —with a slide 1, which constitutes a strip-feeding member for bringing a strip into engagement with the feed-rollers i , above referred to.

5 In the present instance the slide 1 is shown provided with a dog 2, which may be actuated by a spring 3 to force said dog into engagement with a strip resting upon the ledge 4 of the slide, a suitable positioning-gage (not 10 shown) being provided, so that the strips may be carried into contact with the feed-rollers in a uniform manner.

It will now be understood that as soon as the first set of feed-rollers have engaged the 15 strip the latter will be withdrawn from under the dog 2 and will be carried into engagement successively with the other feed-rollers of the series, and thence into contact with a guide 5, which is preferably V-shaped in cross-section to correspond to the tapering cross-section of the strip. As the strip enters the 20 guide 5 it may come into contact with a blade-spring 6, which constitutes a device whereby the strip is firmly seated in the guide 25 5, near one end thereof, while near its other end said strip is retained in position within the guide 5 by a presser-bar 7, which in the present instance is pivoted at 8 and which is operative to force the strip into contact 30 with the guide upon the engagement of a strip with the last feed-roller i and its companion friction-roller l and upon the upward movement of the latter.

The construction shown in the drawings 35 comprises a lever 9, also fulcrumed at 8 and having its free end connected by a pin 10 with the forward end of the presser-bar 7, while the rear end of said lever 9 is connected by a pin 11 with a lever 12, resting with 40 one end upon a shoulder 13, formed in the frame o , and its other end is engaged by a plunger 14, which is mounted for vertical movement in the frame o , a spring 15 being employed for normally forcing said plunger upward, and thus depress the presser-bar 7, 45 as will be readily understood.

Inasmuch as it is desirable to withdraw the presser-bar 7 from the guide as soon as the strip has passed beyond the feed-rollers, 50 means are provided whereby the plunger 14 will be depressed against the action of the spring 15, and consequently the presser-bar 7 will be withdrawn from the guide 5, these means consisting, substantially, of an abutment-screw 16, held in the last bar m , so that after the strip has passed from under the last friction-roller l the lever 12 will be depressed by the descending bar, the spring r being stronger, as a matter of course, than the 60 spring 15.

From the foregoing it will be seen that the strip will be positively guided, the guide 5 being preferably stationary, so that the knife or cutter co-operative with said guide is organized so as to traverse across the longitudinal path of the strip. This knife or cutter is herein designated by 17 and consists, sub-

stantially, of a blade having an edge 18 and preferably held in a knife-holder 19, so that said knife may have a slight swinging movement to accommodate itself to the angle of the slit path relative to the longitudinal axis of the advancing strip, and while in the present instance I have shown said holder pivoted in alinement with the knife-edge it 70 should be noted that said knife-edge may be disposed in the rear of the pivot-support of the holder, so as to allow the knife to find its own position by virtue of the force supplied by the advancing strip. On the other hand, 80 it should be noted that the knife-edge should not be remote from the pivot-support of the holder, and thus not defeat the action of the proper guiding of the knife-edge transversely of the strip. 85

The knife 17 is adjustably held within the holder 19 by screws 20 and check-nuts 21, while at the same time said holder comprises a jaw 22, which may be caused to engage the side of the knife 17—as, for instance, by a screw 23—and force the knife against the body of the holder, as clearly shown in Fig. 4. By the adjustment of the screws 20 the knife-edge may be adjusted to and from the pivotal axis of the holder, and by the screw 23 95 clamped in its adjusted position, the screws 20 serving as a rear bracing for the knife, as will be readily understood.

The knife-holder 19 is shown pivotally supported on pintles 24, each having a V-shaped 100 recess to receive the knife-edge and held in or forming a part of projections 25, formed on a slide or carrier 26, which is mounted for reciprocation in a frame 27, secured upon the table a . Also held on the slide 26 is a separating member 28, substantially V-shaped in horizontal section, as is shown by dotted lines in Fig. 4, said member 28 being positioned in the rear of the knife 17, substantially with the apex thereof adjacent to the knife, so that 105 as the strip is fed forward past the knife the complementary branches of the slitted strip will be separated and deflected from the sides of the knife, in this manner not only insuring the knife against undue wear at the sides 110 thereof, but, furthermore, giving free action to the knife when cutting the strip. 115

Referring to Figs. 1 and 2, it will be seen that the vertical shaft v carries near its upper end a cam 29 in engagement with a roller 120 30, pivotally held on a slide 31, which may straddle the shaft v and to which a reciprocatory movement is imparted by the cam 29. The rear end of the slide 31 is provided with a projection 32, adapted to enter a recess 33, 125 provided therefor in the slide 26 and interposed between the ears 34 and 35, projecting from the body portion of the slide 26, as is clearly shown in Fig. 6. The projection 32 is somewhat narrower than the recess 33, so 130 that the slide 26 may be positioned relatively to the slide 31 to vary the effective working zone of the knife 17 relative to the stationary guide 5. This variation is accomplished in

the present instance by adjusting-screws 36 and 37, the inner ends of which are adapted to enter suitable recesses in the projection 32 and in this manner hold the slide 31 in fixed 5 position relative to the slide 26.

From the foregoing description it will be understood that the knife-operating slide 26 may be adjusted relatively to the slide 31 for an amount equal to the difference in size between the projection 32 and the extent of the recess 33.

In order to determine the relative positions of the slides 31 and 26, suitable index-marks, such as 38, may be provided on one of said 15 slides and to coöperate with a datum-line provided on the other.

Inasmuch as in some instances it may be desirable to move the knife-supporting slide 26 entirely out of the way in order to obtain 20 access to the guide 5 or some other mechanism, I have herein shown a device whereby the slide 31 may be moved bodily and without being influenced by the action of the cam 29.

In the construction shown in Fig. 1 it will 25 be seen that the slide 31 carries a lever 39, pivoted on the slide 31, as at 40, and provided with a pin 41, to which one end of a spring 42 may be secured, while the other end of said spring may be attached to the base *a* in any 30 suitable manner.

When the parts are in the position shown in Fig. 1, the spring 42 will of course tend to keep the roller 30 in contact with the cam 31, while when it is desired to move said slide in 35 the direction of the belt-pulley *d* the lever 39 may be swung around its fulcrum 40, in this manner relieving the slide 31 of the action of the spring 42, as will be readily understood.

The operation of my improved machine is 40 as follows: The strip which my machine is particularly adapted to slit forms a segment substantially uniform from end to end of a cylindrical body of ratan, from which it is cut somewhat after the manner shown in Fig. 8. 45 The end of the strip may now be passed under the dog 2 of the primary feed-slide 1, which will carry the forward end thereof into contact with the first set of feed-rolls *i*, which are continuously rotating, and will therefore propel the strip so as to be engaged by the entire 50 series of feed-rollers *i* and friction-rollers *l*. As soon as the forward end of the strip has passed beyond the last set of feed-rollers it will enter the stationary guide 5 and encounter the spring 6, whereby said strip is forced to a seat in said guide, while at the same time the presser-bar 7 has been depressed by the action of the spring 15, so that the strip is firmly seated within the guide 5, and for this 55 reason retain its forward line of travel uniformly. As the strip is now fed forward the knife 17 will through the intervention of the slide 26 be moved crosswise of the path of the strip, so that the knife-edge will commence 60 to slit said strip diagonally of the length thereof, the knife-edge traversing substantially as indicated by the line 43 in Fig. 9. The pri-

mary position of the knife is shown in the first diagram of Fig. 10, while the succeeding diagrams illustrate the positions of the knife-edge during consecutive equal portions of longitudinal travel of the strip, the shaded portions of the diagrams illustrating clearly the cross-section of the strip at these respective points during the longitudinal travel of 75 the strip, so that by comparison of the first diagram of Fig. 10 with the last one of the series it will be seen that the knife has a travel gradually from left to right, and will therefore slit the strip into two complementary parts, 80 one of which is shown in side view in Fig. 11. This strip may be trimmed to the form of a true slender conic segment or to a modification thereof suitable for a whip-stock-forming strip by the removal of proportionately 85 less of the surplus relatively to the final cross-sectional form to be produced at the tip half of the strip than at the butt portion. As soon as the rear end of the strip has been released from or has passed the last set of feed-rollers the last friction-roller *l* will immediately be forced toward the roller *i*, in this manner raising or withdrawing the presser-bar 7 from the guide 5 and leave the strip practically free in said guide. As the next 95 strip is being fed in and the primary feed-slide 1 again makes a forward movement the end of the first strip may be ejected from the guide 5 by the forward end of a thrust-rod 44, the rear of which is in the present instance pivotally supported on the feed-slide 1, the ejecting end of said rod resting in its inactive position on an inclined guide 45, disposed between the sections of the last feed-roller, and the upper face of which will tend 100 to direct the end of the rod 44 into alinement with the guide 5 and, striking the rear end of the strip in the guide that has just cleared the last pair of rolls, will thrust the strip through the guide and complete the cutting 105 of the strip, as may be clearly seen in Fig. 5.

The machine may be so arranged that the knife instead of commencing to diagonally slit the segmental strip at its end may commence such slitting several inches from the 115 end, and thus produce strips which may be finally made into whips having cylindrical butts and forwardly-tapering bodies. Moreover, the rapidity of traverse of the knife across the path of the strip may be easily varied in either of two ways—firstly, by replacing for the cam which operates the knife-carrying slide one of different grade, or, secondly, by substituting for the gear *e* one of different diameter, correspondingly adjusting 120 the intermediate gear *f*.

I am of course aware that it is not broadly new to provide a mechanism for dividing a strip, such as ratan, from end to end on a line inclined to the longitudinal line of the 130 strip by a movement relatively between the cutter or slitting tool and the guide through which the strip is fed, and it is not my intention to broadly claim such a mechanism,

nor broadly to claim a spreading or separating device located in the line of feed beyond the knife.

Having thus described my invention, what I claim, and desire to secure by Letters Patent, is—

1. In a machine for dividing a cross-sectionally V-shaped strip of fibrous material, such as ratan, on a surface diagonal to the strip, the combination of two members, one member being a guide for the strip having a V-shaped opening whose convergent sides are arranged to constitute substantial bearings for the convergent sides of the tapered strip, and the other member being a dividing-cutter located beyond the guide, one of said members being arranged to be moved relative to the other member and thereby cause the cutter to traverse the area of the V-shaped opening in the guide from one side of the V to the other, whereby complementary divisions of the strip are produced.

2. In a machine for dividing a cross-sectionally V-shaped strip of fibrous material, such as ratan, on a surface diagonal to the strip, the combination of a guide for the strip having a V-shaped opening whose convergent sides are arranged to constitute substantial bearings for the convergent sides of the tapered strip, a carrier located beyond the guide, a splitting-knife mounted on the carrier with its cutting edge substantially parallel with a line bisecting the angle of the V-shaped opening in the guide, the carrier being arranged to be moved bodily across the area of the V-shaped opening in the guide from one side of the V-opening to the other.

3. In a machine for dividing a cross-sectionally V-shaped strip of fibrous material, such as ratan, on a surface diagonal to the strip, the combination of a guide for the strip having a V-shaped opening whose convergent sides are arranged to constitute substantial bearings for the convergent sides of the tapered strip, a carrier located beyond the guide, a splitting-knife mounted on the carrier with its cutting edge substantially parallel with a line equally bisecting the angle of the V-shaped opening in the guide, the carrier being arranged to be moved and thereby carry the knife bodily across the area of the V-shaped opening in the guide from one side of the V-opening to the other.

4. In a machine for dividing a cross-sectionally V-shaped strip of fibrous material, such as ratan, on a surface diagonal to the strip, the combination of a guide for the strip having a V-shaped opening whose convergent sides are arranged to constitute substantial bearings for the convergent sides of the tapered strip, a carrier located beyond the guide, a splitting-knife pivotally mounted on the carrier with its axis lying in the same plane as the cutting edge, the cutting edge of the knife being substantially parallel with a line bisecting the angle of the V-shaped opening in the guide, the guide and the carrier being

so arranged that one of these members may be moved relative to the other and thereby cause the knife to traverse the area of the V-shaped opening in the guide from one side of the V to the other.

5. In a machine for dividing a cross-sectionally V-shaped strip of fibrous material, such as ratan, on a surface diagonal to the strip, the combination of a guide for the strip having a V-shaped opening whose convergent sides are arranged to constitute substantial bearings for the convergent sides of the tapered strip, a dividing-cutter located beyond the guide, one of said members being arranged to be moved relative to the other and thereby cause the cutter to traverse the area of the V-shaped opening in the guide from one side of the V to the other, means for feeding a strip through the guide, means connected with said feeding means for operating said movable member, and means for adjusting the normal location of the cutter with respect to the feeding means toward and from the V-shaped opening.

6. In a machine for dividing a cross-sectionally V-shaped strip of fibrous material, such as ratan, on a surface diagonal to the strip, the combination of a guide for the strip having a V-shaped opening whose convergent sides are arranged to constitute substantial bearings for the convergent sides of the tapered strip, means for pressing the strip in contact with the engaging sides of the guide, and a dividing-cutter located beyond the guide, one of said members being arranged to be moved relative to the other and thereby cause the cutter to traverse the area of the V-shaped opening in the guide from one side of the V to the other.

7. In a machine for dividing a cross-sectionally V-shaped strip of fibrous material, such as ratan, on a surface diagonal to the strip, the combination of a guide for the strip having a V-shaped opening whose convergent sides are arranged to constitute substantial bearings for the convergent sides of the tapered strip, a carrier located beyond the guide, a splitting-knife mounted on the carrier with its cutting edge substantially parallel with a line bisecting the angle of the V-shaped opening in the guide, the carrier being arranged to be moved and thereby carry the knife bodily across the area of the V-shaped opening in the guide from one side of the V-opening to the other, and means secured to the carrier beyond the knife and arranged to separate the divisions of the strips produced by the cutter.

8. The combination of a work-supporting member; a knife-supporting member, and a knife pivotally mounted on the latter member; one of said members being arranged to be moved relative to the other member in a path transverse to the pivotal axis of the knife.

9. The combination of a work-supporting member; a knife-supporting member; and a

knife pivotally mounted on the latter member with its cutting edge parallel with its pivotal axis; one of said members being arranged to be moved relative to the other in a path transverse to the pivotal axis of the knife.

10. The combination of a work-supporting member; a knife-supporting member; and a knife pivotally mounted on the latter member with its cutting edge not coincident with its pivotal axis, and the shearing sides of the knife converging in a direction toward said axis; one of said members being arranged to be moved relative to the other member in a path transverse to the pivotal axis of the knife.

11. The combination of a work-supporting member; a knife-supporting member; and a knife pivotally mounted on the latter member with its cutting edge parallel with its pivotal axis, but not coincident therewith, and the shearing sides of the knife converging in a direction toward said axis; one of said members being arranged to be moved relative to the other member in a path transverse to the pivotal axis of the knife.

12. The combination of a work-supporting member; means for feeding a strip through said member, a knife-supporting member; and a knife pivotally mounted on the latter member; one of said members being arranged to be moved relative to the other member in a path transverse to the pivotal axis of the knife.

13. The combination of strip-feeding means, a V-shaped guide for the strip, and a presser-bar controlled by the strip-feeding means and arranged to be withdrawn from the guide by the feeding means after the passage of a strip therethrough.

14. The combination of a pair of coacting feed-rolls, a V-shaped guide for the strip, and a presser-bar controlled by the bodily movement of one of said feed-rolls relative to the other.

15. The combination of a pair of coacting feed-rolls, a V-shaped guide for the strip, and a presser-bar controlled by the bodily movement of one of said feed-rolls relative to the other and arranged to be thereby withdrawn from the guide after the passage of a strip through the rolls.

16. The combination of a pair of coacting feed-rolls, yieldable means for normally forcing the rolls together, a V-shaped guide for the strip, and a movable presser-bar controlled by the bodily movement of one of the rolls relative to the other and arranged to be withdrawn from the guide after the passage of a strip through the feed-rolls.

17. The combination of strip-feeding means, a V-shaped guide for the strip, a presser-bar cooperative with the feeding means for retaining a strip in engagement with the guide; and means near one end of the guide for seating a strip therein.

18. The combination of strip-feeding means, a V-shaped guide for the strip, a presser-bar cooperative with the feeding means and ar-

ranged to engage the strip at one end of the guide and thereby retain the strip in engagement with the guide, and means located at the other end of the guide for seating a strip therein.

19. In a machine of the class described, the combination of one or more pairs of coacting feed-rolls, one of said rolls having a substantially V-shaped periphery and an annular slot at the bottom of the V; and a reciprocatory thrust-bar lying normally in said slot and below the V-shaped area of the rolls; and means for bringing said bar into the work-engaging area of the rolls at a certain part of its movement.

20. In a machine of the class described, the combination of one or more pairs of coacting feed-rolls, one of the rolls having a substantially V-shaped periphery and an annular slot at the bottom of the V; a reciprocatory feed-slide operatively connected with the rolls; a thrust-bar having one end connected with the feed-slide, said bar lying normally in the said slot and out of the V-shaped area of the rolls; and means for bringing the free end of the thrust-bar into the work-engaging area of the rolls at a predetermined part of its thrust movement.

21. In a machine of the class described, the combination of one or more pairs of coacting feed-rolls, one of the rolls having a substantially V-shaped periphery and an annular slot at the bottom of the V; a reciprocatory feed-slide operatively connected with the feed-rolls; a thrust-bar having one end connected with the feed-slide, the bar lying normally in said slot and out of the V-shaped area of the rolls; and a cam arranged to engage said bar and bring the free end thereof into the work-engaging area of the rolls at a predetermined part of its movement.

22. In a machine of the class described, the combination of a guide for a strip, a pivoted presser-bar arranged to engage a strip in the guide, a lever connected with the presser-bar, a pair of coacting rolls, one of the rolls being movable to and from the other, and means for causing the bodily movement of the roll to operate the lever and presser-bar.

23. In a machine of the class described, the combination of a guide for a strip, a pivoted presser-bar arranged to engage a strip in the guide, a lever connected with the presser-bar, a pair of coacting rolls, one of the rolls being movable to and from the other, means for causing the bodily movement of the roll to operate the lever and presser-bar, a spring acting on the lever and tending to retain it with the presser-bar in the strip-engaging position, and a second spring tending to force the rolls together, the latter spring being arranged to overcome the effect of the other spring.

24. In a machine of the class described, the combination of a guide for a strip, a pivoted presser-bar arranged to engage a strip in the guide, a lever connected with the presser-bar,

a pair of coacting rolls, a hinged bar having one of said rolls pivoted thereon and arranged to move to and from the other roll, a spring arranged to engage said lever and tending to retain it with the presser-bar in the strip-engaging position, and a spring acting on said hinged bar and tending to force the rolls together, the latter spring being arranged to overcome the effect of the other spring.

10 25. In a machine of the class described, the combination of a guide for a strip, a pivoted presser-bar arranged to engage a strip in the guide, a lever having one end connected with the presser-bar, a second lever having one end engaging the other end of said pivoted le-

ver, said second lever having its other end supported in a hinged manner, a spring engaging said levers and tending to move them and thereby force the presser-bar toward said guide, a pair of coacting rolls, one of the rolls 20 being bodily movable to and from the other, and means for causing the bodily movement of the roll to operate said lever and thereby move the presser-bar to and from the guide.

Signed by me at Springfield, Massachusetts, 25 this 8th day of June, 1901.

HENRY W. LARSSON.
